UNITED STATES PATENT OFFICE.

LEWICKI J. LEON, OF WEST CHICAGO, ILLINOIS.

DESIGN FOR A BASE FOR BIRD CAGE OR OTHER STANDS.

Application filed December 12, 1927. Serial No. 24,452. Term of patent 14 years.

To all whom it may concern:

Be it known that I, LEWICKI J. LEON, a citizen of the the United States, residing at West Chicago, in the county of Du Page and State of Illinois, have invented a new, original, and ornamental Design for a Base for Bird Cage or Other Stands, of which the following is a specification, reference being had to the accompanying drawing, forming part thereof.

Figure 1 is a top plan view of a base, showing my new design;

Fig. 2 is a side elevational view of the base; and

Fig. 3 is a sectional view through the base on line 3—3 of Fig. 1.

I claim:

The ornamental design for a base for bird cage or other stands, as shown.

LEWICKI J. LEON.
